AUTOMATICALLY CONTROLLED VALVE

Elling O. Weeks, Milwaukee, Wis.

Application May 18, 1934, Serial No. 726,422

4 Claims. (Cl. 137—139)

This invention relates to improvements in an automatically controlled valve, and more particularly to a simple device that automatically controls outside air or vapor supplied to the intake manifold of an internal combustion engine.

An object of this invention is to furnish an easily adjustable means for automatically regulating the amount of free air or vapor supplied to the combustible gas through the intake manifold of an internal combustion motor, without any additional carburetor adjustment.

Another object of this invention is to furnish an automatically controlled valve for supply air or vapor, the amount of vapor being increased as the speed of the engine increases and reduced as the speed of the engine is reduced, taking care of the change in air supply necessary with the variation in engine speed.

With the above and other objects which will be apparent as the description proceeds, my invention consists of the following novel features and method of construction which are illustrated in the accompanying drawings and pointed out in the appended claims.

25 In the accompanying drawings,

Fig. 1 shows the device in its entirety attached to a conventional type of internal combustion engine, supplying the vapor from the crank case, to illustrate the principle of the device.

30 Fig. 2 is a perspective rear view of the automatic control valve.

Fig. 3 is a front view of the automatic control valve.

Fig. 4 is a cross sectional view of the control valve showing the valve arrangement.

Fig. 5 is a fragmentary cross sectional rear view of the automatic control valve showing its detailed construction.

Referring to the drawings in detail where like characters of reference denote corresponding parts, character 10 indicates an internal combustion engine having a fan 11 actuated by belt 12 working off of the crank shaft 13, there is an automatic control valve 14 supported by a conventional bracket 15, which is fastened thereto by screws at 24, and to the engine 10 by means of bolt 16, the tube 17, leading from the breather spout 18 in the crank case of the engine and a tube 19, leading from the control valve 14, to the vapor inlet 20, which is placed between the carburetor outlet 21, and the intake manifold 22, the control valve 14 consists of a housing 23, having holes 24 at its top for attaching bracket 15. The front of the housing 23, has louvres 25 to permit the air to enter.

There are brackets 26 mounted on the inside of housing 23, which support the ends of both tubes 17 and 19, leaving a vertical opening 27, between the tubes. There is a vane 28 having a right angular section 29 with a port 30, this vane 28 is hinged at its center or fulcrum 31 and normally hangs in a vertical position but springs or counterweights or both may be used as a modified means of returning the vane to its normal position. There are radial slots 32 on the side of housing 23 to act as an indicator for vane 28.

In operation the automatic control valve 14 is mounted on the forward end of the engine immediately behind the fan 11, or any other convenient location. In the drawings it is fastened at 24 to an angular bracket or support 15 bolted down onto the engine with bolt 16, there is a tube 17 leading from either the breather spout 18 in the crank case of the engine, the radiator, or any auxiliary air or vapor supply, this tube is led into the control valve 14 terminating at a point near the center of the valve 14 leading to the air or vapor inlet 20 clamped between the flanges of the carburetor 21 and the intake manifold 22, the control valve 14 has a vane 28 pivotally mounted having a flat section 29 at right angle to the vane 28 operating between the ends of tubes 17 and 19 at 27, the flat section 29 of the vane 28 has an aperture or port 30, and when the air from the fan 11 is blown through the louvres 25 into the housing 23 of the control valve 14, the vane 28 is forced backward swinging on its pivot 31 causing the port 30 in the flat section 29 to register with the ends of the tubes 17 and 19.

The operation of the pistons in the cylinders of engine 10 causes a suction, drawing in the gaseous fumes through the intake manifold 22, from the carburetor 21 and in doing so also creates a suction in the tube 19, when the port or aperture 30 registers partially or fully with the end of the tubes 17 and 19 this suction is further proportionately imparted to the tube 17 drawing the air or vapor to mix with the gases in the intake manifold 22.

The entire installation of this device can be made without any mechanical change or alteration in the construction of the internal combustion engine, whether used on automobile, airplane, or motorboat, and will automatically control the amount of air or vapor drawn into the combustion chamber through the intake manifold 22, depending on the velocity of the air contacting the vane in the control valve. It is obvious that the faster the engine is run the greater the velocity of air hitting the vane 28,

whether this air is produced by the fan 11 operated by the crank shaft 13, or whether it is produced by the speed of the automobile, aeroplane, or motorboat. The more air hitting the vane 28 in the control valve 14 the wider it will open the port 30 and the more air or vapor will be drawn into the combustion chamber of the motor.

Having thus described my invention, what I claim and desire to secure by Letters Patent of the United States, is:

1. A valve comprising a housing having louvres in its front wall, a vane within said housing, and pivotally supported from the top wall thereof, inlet and outlet ducts having opposed open ends extending into said housing, and an angular projection on said vane interposed between the open duct ends and having a port adapted to register with the duct openings when said vane is swung on its pivot support from its normally depending position within said housing by pressure of air entering said louvres.

2. A valve, comprising a housing having a perforated front wall, inlet and outlet ducts extending into said housing and having opposed ends disposed in closely spaced relation therein, a pivotally mounted vane, a projecting member car-

ried by said vane, and having a port therein, said member being disposed between the open ends of said ducts and normally closing the same, said port in said projecting member being adapted to register with the open ends of said ducts when said vane is swung on its pivot support by pressure of air entering said perforations.

3. A valve of the class described, comprising a housing open at its rear side and having a perforated front wall, a movable vane disposed in rear of and parallel to said front wall, ducts entering said housing and having opposed open ends disposed in closely spaced relation, and a ported valve body carried by said vane and disposed between the open ends of said ducts, said vane being operable by the pressure of air entering the said perforations to move said valve body to register the port therein with the open ends of said ducts.

4. The valve as set forth in claim 3 wherein the said vane is pivotally suspended from the top wall of said housing and has a lateral projection adjacent its lower end engaged in an arcuate slot formed in a side wall of the housing to stabilize the operative movements of the vane.

ELLING O. WEEKS.
